INVENTOR

PER

Albert J. Gub
ATTORNEY.

UNITED STATES PATENT OFFICE.

W. KEATH SUMMERHAYES, JR., OF LOUISVILLE, KENTUCKY.

ADVERTISING DEVICE.

Application filed May 21, 1926. Serial No. 110,669.

This invention relates to improvements in advertising devices, and has for one of its principal objects the provision of means for displaying signs, placards, notices, advertisements and the like in a simple, convenient manner and with a minimum expenditure of time and trouble.

One of the important objects of this invention is to provide, in an advertising device or the like, elements whereby a sign, pennant, notice, price card, or similar device can be ornamenteally displayed by attachment of the same to any smooth surface, such as plate glass or the like, without in any way damaging or injuring said surface, and further, providing for its ready removal when desired.

Another and further important object of this invention is the provision, in an advertising or display device, of means for presenting any desired subject matter to the public or passersby, such as "For sale" or "For rent", "Auction", or "Fire sale" signs, "Welcome" signs, and similar notices, in a distinctive manner and in conspicuous and noticeable positions.

Other and further important objects of the invention will be apparent from the disclosures in the accompanying drawings and following specification.

The invention, in a preferred form, is illustrated in the drawings and hereinafter more fully described.

In the drawings:

Figure 1 is a perspective view of the improved advertising device of this invention, showing the same as applied to a smooth surface, such as glass or the like.

Figure 2 is a detail view illustrating a portion of the device.

Figure 3 is a sectional view, taken on the line 3-3 of Figure 1.

Figure 4 is a plan view showing the metal stamping or the like from which the apparatus is constructed.

As shown in the drawings:

The reference numeral 10 indicates generally an upright supporting element forming what might be termed the base of the present device, the same being formed from the portion 12 of the blank shown in Figure 4 by being bent or folded into desired shape. As shown in Figure 1, a portion of the device is broken away, illustrating the opening 14 through which passes a gripping ele-

ment 16 to the outer end of which is affixed a rubber vacuum cup or the like 18 by means of which the device can be readily and conveniently applied to any smooth surface, such as a plate glass window or the like.

It will be noted that the openings 14 are wider at the lower end than at the top, so as to allow of a suitable co-operation with and insertion of the member 16 into the opening. Obviously if the rubber vacuum cups are not desired they may be readily removed and the device hung upon nails, screws, or the like fastened to a solid wood or similar surface, to which the application of the rubber vacuum cup is not so desirable.

As best shown in Figures 1 and 2, the flared portions 20 of the blank shown in Figure 4 are bent downwardly to form a suitable bracket or base member, whereby the remainder of the device is supported at right angles to the base element 10.

This portion, designated by the reference numeral 22, is folded over as best shown in Figure 3, and the edges are turned upwardly and inwardly as shown in this figure so that proper gripping or other supporting connection is afforded with a placard, sign, or similar display means 24 upon which any desired printed matter or other illustration may appear, as indicated at 26.

It will be seen that herein is provided a display or advertising means which is simple of construction and economical of manufacture, comprising essentially a single piece of stamped metal or the like. Further, this advertising medium is adaptable to a wide variety of uses and the display means or placard adapted to be associated therewith can be readily changed at will and also may be of any desired shape or material, as cloth, wood, celluloid, and the like, or may be in oval, circular, diamond, or other shape.

Again, the frame itself can be turned so that the placard is viewed from only one side, as by turning the base member 10 through an angle of ninety degrees with respect to the extending arm 22. The fact that the placard 24 can be seen from both sides when the device is attached to a glass window or the like is an obvious advantage.

I am aware that many changes may be made and numerous details of construction varied throughout a wide range without departing from the principles of this invention.

tion, and I therefore do not purpose limiting the patent granted hereon otherwise than as necessitated by the prior art.

I claim as my invention:

In an advertising device, a display means comprising a single sheet of stamped material including three portions connected to each other, a base member, a bracket member and an arm member, said base member comprising a rectangular element connected to the remaining portions by a substantially narrow strip at the side of one of its shorter edges and adapted to be bent double longitudinally to provide front and rear faces, the rear face having openings for the reception of supporting elements; the bracket member being adjacent the base member and

comprising a polygonal element having two parallel sides and two angularly converging sides disposed at approximately right angles to each other, the longer of the parallel sides being adjacent the bracket member, and the whole element adapted to be doubled upon itself along substantially a central line to contact with the base element in a supporting position; and an extending arm comprising a rectangular strip doubled upon itself longitudinally and provided with inwardly and upwardly turned edges having a space therebetween for the reception and rejection of a placard.

In testimony whereof I affix my signature.

W. KEATH SUMMERHAYES, JR.
